UNITED STATES PATENT OFFICE.

EBEN J. STEVENSON, OF BOSTON, MASSACHUSETTS.

MEANS FOR VENTILATING TELEPHONE-BOOTHES.

1,207,090.

Specification of Letters Patent.

Patented Dec. 5, 1916.

Application filed June 14, 1915. Serial No. 33,902.

To all whom it may concern:

Be it known that I, EBEN J. STEVENSON, a citizen of the United States, residing at Boston, in the county of Suffolk, in the State of Massachusetts, have invented a new and useful Means for Ventilating Telephone-Booths, of which the following is a specification, reference being had to the accompanying drawings.

- 10 The immediate object of this invention is to provide extremely simple, cheap, and positively acting means for automatically energizing, and setting in operation, an electric fan in a telephone booth, whenever the 15 telephone is used. Booths of this type, as now commonly provided, are designed to be tightly closed while they are being used, in order that the conversation may not be overheard and, when they are thus closed, the 20 air in the booth becomes foul and heated, particularly in hot weather, and the intent of this invention is to provide a circulation of the air in the booth and to thereby cool said air in an appreciable degree.
- 25 Briefly described my invention comprises an overhead fan which is wired in circuit with a suitable battery or other source of electric energy, and a make-and-break for said circuit which serves also as the hook 30 upon which the telephone receiver is hung when the telephone is not in service.

My invention is illustrated in the annexed drawing which is a vertical, sectional, view of a telephone booth, having located therein 35 a fan and means, embodying my present improvement, for automatically starting and stopping the said fan.

Referring to the said drawing, the letter *a* indicates a booth, *b* a wall telephone mounted 40 in said booth, and *c* denotes an electric fan mounted overhead in the booth.

d indicates a battery and *e* the receiver hook of the telephone, said hook being of the ordinary type, that is to say it is hinged

at its inner end portion and the receiver-supporting end is adapted to be raised a limited distance, by a suitable spring, whenever the receiver is removed from the hook. As here illustrated one pole of the fan magnet or motor is connected with the battery 50 by a wire *f*, the other pole of the battery being connected with the receiver hook by a wire *g*, and the other pole of the fan motor is connected by wire *h* with a fixed contact *h* which is located immediately in the path of the receiver-hook arm *e* but out of engagement with said arm when the receiver is hanging on the hook, and as seen in the annexed drawing. So long as the telephone is not in service, and the receiver remains 55 on the hook, the described circuit is open and the fan is still but the instant that the receiver is removed from the hook the arm *e* moves upward, into engagement with the contact *h*, thus closing the said circuit and 60 energizing the fan motor, which continues to run until the receiver is returned to the hook and the circuit is automatically opened. Thus it will be seen that the fan 65 is controlled as to its starting and stopping by the use and disuse of the telephone, and this desirable result is attained with practically no additional expense.

Having thus described my invention, I claim as new and wish to secure by Letters 75 Patent:—

A device of the type described, including a telephone, an electric circuit, a motor-controlled fan, with a source of electric energy, a resiliently actuated pivoted hook for 80 the receiver, a contact-point wired to one pole of the fan-motor, said contact-point being arranged to be automatically engaged by said hook upon the removal of said receiver from the hook, said fan-controlled 85 motor and receiver hook being included in the said electric circuit.

EBEN J. STEVENSON.
